JOHN S. GOLDBERG AND RAYMOND M. ANDERSON, OF CHICAGO, ILLINOIS, ASSIGNEES
TO STROMBERG MOTOR DEVICES COMPANY, OF CHICAGO, ILLINOIS, A CORPORA-
TION OF ILLINOIS.

CARBURETER.

1,355,960.

Specification of Letters Patent. Patented Oct. 19, 1920.

Application filed March 6, 1911. Serial No. 612,683.

To all whom it may concern:

Be it known that we, JOHN S. GOLDBERG and RAYMOND M. ANDERSON, both citizens of the United States, residing at Chicago, 5 in the county of Cook and State of Illinois, have invented a certain new and useful Improvement in Carbureters, of which the following is a full, clear, concise, and exact description, reference being had to the accompanying drawings, forming a part of 10 this specification.

Our invention relates to carbureters and contemplates improved means for feeding the fuel.

15 As is well-known in the art, it has been the practice in many instances to provide a main air inlet and a main fuel inlet, and, in addition, an auxiliary air inlet and associated fuel inlet, the latter inlets coming 20 into play only after the engine has created a sufficient suction in the mixing chamber. Devices somewhat like this but omitting the auxiliary fuel supply also have been provided.

25 Our invention is concerned with a fuel feeding means which is adapted to remain inoperative until the predetermined vacuum has been attained, and to the end of a simple, effective and reliable means, we provide a 30 direct passage from the float or secondary storage chamber to the mixing chamber or air passage connected directly therewith. So that this feeding device may remain inoperative until the proper time, I provide a 35 "shunt" or parallel path of sufficiently low resistance, which shunt must be first satisfied in order that the fuel itself may respond.

Our invention is illustrated in the accompanying drawings in which—

40 The figure is a side elevational view of the carbureter.

The main structural supporting unit is in the form of a casting 6 which may be considered as being divided into three parts—the main mixing chamber 7, the auxiliary air inlet chamber 8 and the oil inlet chamber 9, the three parts conveniently having their axes in a single plane. The main mixing 45 chamber 7 is supplemented downwardly by an extension 10 which has a central passage-way of double conical cross-section, commonly called a "Venturi" tube. The extension 10 is screw-threaded externally for

the reception of a sleeve 11 which then extends downwardly and is provided at the bottom with a preferably integral shelf 12. A fuel tube 13 is disposed in axial alinement with the sleeve 11, part of the tube extending upwardly into the sleeve and the other part 60 extending downwardly below the shelf 12. This fuel tube is conveniently cast integral with the sleeve 11 and shelf 12 and is supported therefrom by means of the spider 14. A circular wall 15, preferably of glass, is 65 clamped between the shelf 12 and the body of the casting 6 so as to form an oil float chamber 16, suitable gaskets 17 and 18 being provided to make a tight compartment. The float chamber 16 is connected with the 70 inside of the fuel tube 13 by means of the passageways 19, 19 in the spider 14. Disposed within the float chamber and surrounding the sleeve 11, so as to be in axial alinement with the Venturi tube, is an annular float 20, the position of this float being subject to the amount of oil contained in the chamber. The float chamber 16 is connected with the fuel chamber 9 by means of a passageway 21 and the chamber 9 in 80 turn is connected with a source of oil supply in the following manner: The fuel chamber 9 is provided with a double outlet boss 22, 23, a valve seat member 24 being disposed in the connecting passage between the boss 85 chamber and the fuel chamber. The boss 22 is in axial alinement with the passage leading to the fuel chamber and with a valve to be described. This boss is closed however by the use of a plug 25 and it is provided 90 mostly for structural purposes although, as will be evident to those skilled in the art, the fuel could be led into this boss if the associated arrangement were so disposed that that would be convenient. The boss 23 95 is provided with a union 26 from which the pipe 27, leading to the oil supply, extends. A strainer 28 is disposed in the boss 23 so as to prevent impurities from clogging the passage 29, leading to the boss chamber, and 100 subsequent passages.

On the top of the casting 6, in axial alinement with the valve opening 30 in the valve seat member 24, a tubular boss 31 is provided and this boss is internally screw-threaded for the reception of a sleeve 32 in which a valve stem 33 is mounted. At the bottom thereof this valve stem 33 is provided

with a head 34 between which and the sleeve 32 a helical spring 35 is disposed, this spring tending to move the stem downwardly. A valve 36 is carried in this head and the lower 5 end of the valve is tapered for co-operation with the tapered seat for the valve opening 30. The valve, and consequently the stem, is guided at the bottom by means of a suitable spider 37 carried by the valve seat member 10 24. At the top the stem is provided with a cup 38 which surrounds the sleeve so as to protect the passage therethrough. The sleeve 32 carries the cup 39 which is knurled to make a thumb piece and which surrounds 15 the boss 31. The outside of the cup 39 is provided with a plurality of notches 40 into any one of which a plunger 41, disposed in a socket 42 in the casing against the tension of a spring 43, may be disposed. It is clear 20 that when the cup 39 is turned one way or the other the screw-threaded relation between the sleeve 32 and the boss 31 will result in the vertical adjustment of the valve and that the plunger arrangement which has 25 just been described will hold the cup in any adjusted position with sufficient security.

Within the fuel chamber 9 a lever 44 is mounted upon a pivot 45, one arm of this lever being bifurcated so as to engage the 30 under side of the head 34 of the stem 33 and the other arm extending through the passageway 21 into the float chamber 16. The end of the lever 44 within the float chamber has pivoted thereto at 46 a link 35 47 which is attached to the float 20. It will now appear that the oil used for fuel can enter the carburetor by way of the connection 27, passing through the opening 29 and up through the valve opening 30. It 40 then flows over the side of the float chamber and down through the passageway 21. It will be seen that the weight of the float acts in opposition to the spring 35 and as the float rises this opposition will be removed and 45 the spring 35 will tend to close the valve 36 to a greater or less extent. When sufficient oil has entered the float chamber the valve can be closed entirely and when the float subsequently drops it is opened to admit 50 more oil.

The valve 36 can be operated manually by grasping the cup 38. An air inlet 52 is provided in the casing so that the fuel chamber 9 will be exposed to atmospheric pressure and the float chamber itself is connected with the interior of the fuel tube by means of the passageways 19, 19 as heretofore described.

The fuel tube 13 is provided at the upper 60 end with a nozzle 53 which terminates in the restricted zone of the Venturi tube. At the bottom this fuel tube is provided with the normally closed drain cock 54, and is externally screw-threaded for the reception of 65 the priming cup 55. When the float cham-

ber is flooded, as heretofore described, the oil runs out of the nozzle and drops down to this cup. As the air is drawn through the carburetor, then, this excess oil supply is volatilized and a rich mixture is secured 70 for starting purposes.

The auxiliary air chamber 8 is provided with an upward opening in which a spider 56 is disposed, this spider having a number of inlet openings and having its inner edge 75 inwardly beveled as indicated at 57 to form a valve seat. A valve member 58 is secured upon a valve stem 59 which is guided at the top in the central boss 60 on the spider 56 and at the bottom in a sleeve 61 having 80 threaded engagement with the inside of a downwardly extending boss 62 on the main casting. A helical spring 63 surrounds the stem 59 and extends between the under side of the valve member 58 and the top of the 85 sleeve 61. The sleeve has secured thereto a cup 64, which is knurled to form a thumb piece and is provided with a plurality of peripheral slots 65 into any one of which a plunger 66 mounted in a pocket 67 against 90 the tension of a spring 68, may extend so as to hold it in any adjusted position. It will be seen that the manipulation of the cup 64 will result in a change in the tension of the spring 63. For convenience the pocket 67 95 is formed in a screw 69 which is mounted in the main casting.

Near the top of the valve stem 59 a cup 70 is slipped thereover and has threaded engagement with the boss 60. The end of 100 the stem 59 is screw-threaded for the reception of a nut 71 through which a cotter pin 72, which also passes through an opening in the stem, may extend to hold it in any adjusted position. Helical springs 73, 73' are 105 disposed between the nut 71 and the cup 70 and the arrangement is such that these springs do not come into play until after the spring 63 has been compressed to a predetermined extent. The springs 73, 73' are 110 thus called the "high speed" springs. The cup is knurled to form a thumb piece and is provided with a plurality of peripheral slots or grooves 74, 74 into any one of which a plunger 75 disposed in a socket 76 against 115 the tension of a spring 77, may extend. The pocket 76 is provided in a screw 78 which is threaded into the spider 56.

Associated with the auxiliary air inlet is an auxiliary fuel feed device in the form of 120 a nozzle 79 which extends through the casting wall from the float chamber into the auxiliary air chamber or substantially the mixing chamber proper. This nozzle is screwed in place and is locked in position 125 by means of a nut 80. Extending down from the nozzle, to a point below the normal level of the oil in the float chamber, is a tube 81. A vent 82 connects the nozzle passage with the atmosphere in the float chamber. 130

Until the engine has reached the predetermined speed the suction upon the auxiliary nozzle will be satisfied by the vent 82, and the oil in the tube 81 will not respond.

5 When, however, the necessary suction is attained the oil will respond and is volatilized by the rush of air through the auxiliary air chamber, the auxiliary air valve being adjusted to also respond to this suction.

10 In this way a simple, effective and reliable device, for the purposes of a secondary feed, is secured.

The connection between the mixing chamber of the carbureter and the engine is controlled by means of the usual throttle 83.

15 We claim as new and desire to secure by Letters Patent:

1. In a carbureter, a main member forming a mixing chamber with an auxiliary air chamber on one side and a fuel chamber on the other, said member having a downwardly extending tubular boss for the passage of air, a main fuel tube extending upwardly into said boss, a float chamber surrounding said boss, an automatically controlled opening for said auxiliary air chamber, a valve for controlling the admission of fuel to said fuel chamber, a float in said float chamber for controlling said last named valve, an auxiliary fuel feed leading directly from said float chamber to the auxiliary air chamber, and a vent for said auxiliary feed in said float chamber above the level of the oil, said float chamber being connected with the atmosphere.

2. In a carbureter, a mixing chamber, a fuel chamber, a main air inlet, a main fuel inlet, an automatically controlled auxiliary inlet adapted to operate only upon the attainment of a predetermined suction in the mixing chamber, an auxiliary fuel feed leading from said fuel chamber to said mixing chamber, and a restricted permanent vent for said auxiliary feed which is of such size that it will meet the demand of suction in the mixing chamber until the predetermined point has been reached, when the fuel itself will respond.

3. In a carbureter for internal-combustion engines, a casing providing a carbureting-chamber and having a Venturi tube cast integrally therewith and extending downwardly therefrom, said Venturi tube being externally screw-threaded, a tube screwed on to said Venturi tube and carrying an annular shelf, an annular wall surrounding said second-named tube and clamped be-

tween said casing and said shelf to form a fuel-chamber, means for determining a constant level of liquid fuel in said chamber, 60 and a fuel-nozzle disposed in said Venturi tube and fed from said fuel-chamber.

4. In a carbureter having a throttle-valve-controlled outlet, a float chamber having a fuel supply opening, a float in the chamber, 65 a valve connected with the float for closing said opening to preserve the level of the fuel in the float chamber approximately constant, a primary fuel nozzle communicating with said chamber, a main air inlet located 70 adjacent to said primary fuel nozzle, a tube extending into the float chamber between the float and the outer wall of the chamber, said tube being threaded into the upper wall of the float chamber and terminating in a 75 secondary fuel nozzle considerably above the level of the liquid in the float chamber, a secondary air inlet, a passage for the air admitted through said last named inlet, said secondary fuel nozzle being located in said 80 passage and being always open to the suction of the engine when the throttle valve is open.

5. In a carbureter, having an outlet adapted to communicate with the engine, a 85 valve controlling said outlet, a float chamber having a fuel supply opening, a float in the chamber, a valve connected with the float for closing said opening to preserve the level of the fuel in the float chamber approximately constant, a primary fuel nozzle communicating with said chamber, a main air inlet located adjacent to said primary fuel nozzle, a tube extending into the float chamber between the float and the wall of 90 the chamber, said tube having an inwardly extending off-set portion and an enlarged portion extending from said off-set portion terminating in a secondary fuel nozzle considerably above the level of the liquid in 100 the float chamber, a secondary air inlet, a passage for the air admitted through said last named inlet, said secondary fuel nozzle being located in said passage and being always open to the suction of the engine when 105 the throttle valve is open.

In witness whereof, we hereunto subscribe our names, this 4th day of March, 1911.

JOHN S. GOLDBERG.
RAYMOND M. ANDERSON.
